UNITED STATES PATENT OFFICE.

JOHN BESANSON, OF TITUSVILLE, PENNSYLVANIA, ASSIGNOR OF ONE-HALF
TO HERMAN STERN, OF CLEVELAND, OHIO.

PROCESS OF RENOVATING PLUSH OR CLOTH.

SPECIFICATION forming part of Letters Patent No. 309,124, dated December 9, 1884.

Application filed May 8, 1884. (No specimens.)

To all whom it may concern:

Be it known that I, JOHN BESANSON, a citizen of the United States, residing at Titusville, in the county of Crawford and State of Pennsylvania, have invented certain new and useful Improvements in Processes of Cleaning and Dyeing Plush or Cloth, of which the following is a specification.

My invention relates to certain improvements in cleaning and coloring dirty and faded plush or cloth, and is designed, principally, to be used in cleaning and coloring the cloth or plush on railroad-car seats, which operation can be done without removing the cloth from the seats. The process is also applicable to cloth or plush, whether loose or secured to any object. The seats and backs, having been preferably removed from their supports, are thoroughly dusted. Any spots or stains or dirt of any nature are first removed by applying a compound of soap, oxalic acid, and ammonia. Having thoroughly cleaned the fabric it is then subjected to the coloring process. If it be desired to color red, the following ingredients are used: Tartaric acid, oxalic acid, borax, alum, and sulphite of cochineal; to color blue, acid blue, sulphuric acid, borax, alum, and tartaric acid; to color green, metalline green, piperic acid, borax, alum, and 30 tartaric acid. The parts of the different com-

pounds are combined in their proper proportions.

The cleaning and coloring compounds are to be applied with hot or cold water.

It is not essential that a brush be used in the application to loose fabrics, as the processes may be then used without one. After the cloth has dried it may be brushed, and it will then appear as new.

The above-described process is an improvement over the one protected by me in Letters Patent No. 195,334, September 18, 1877.

Having described the invention, what I claim is—

The within-described process of cleaning and dyeing cloth or plush, consisting, first, in removing all dust; then all dirt and stains with a compound of soap, oxalic acid, and ammonia; then coloring with a compound of tartaric acid, borax, alum, and the desired 50 acidated color, after which the article is dried and brushed, cold and hot water being used in applying the compounds, as set forth.

In testimony whereof I affix my signature in presence of two witnesses.

JOHN BESANSON.

Witnesses:
